UNITED STATES PATENT OFFICE.

ALFRED A. E. HANSEN, OF PHILADELPHIA, PENNSYLVANIA.

SELF-FEEDING AND RENEWABLE ERASER ATTACHMENT.

Application filed November 29, 1921. Serial No. 518,607.

To all whom it may concern:

Be it known that I, ALFRED A. E. HANSEN, a citizen of the United States, residing at Philadelphia, in the county of Philadelphia and State of Pennsylvania, have invented certain new and useful Improvements in Self-Feeding and Renewable Eraser Attachments, of which the following is a specification.

10 This invention relates to eraser attachments for pencils and particularly for pencils embodying independent leads and means for feeding the leads one at a time outwardly of the pencil, such as that disclosed in my 15 co-pending application filed Oct. 13, 1921, Serial No. 507,513, and the primary object of the present invention is to provide a novel pencil end embodying an improved means for supporting an eraser, whereby the eraser 20 can be removed when worn and replaced by a new one and whereby the eraser can be exposed to view when needed and so that the entire length of the eraser can be conveniently used up and thereby prevent waste 25 of the eraser.

A further object of the invention is to provide a novel means for connecting the improved attachment to various types of pencils or the like embodying independent 30 leads and ordinary pencils.

A still further object of the invention is to provide an improved eraser attachment for pencils of the above character, which is durable and efficient in use, one that is 35 simple and easy to manufacture, and one which can be placed upon the market and incorporated with pencils at a minimum cost.

With these and other objects in view, the invention consists in the novel construction, 40 arrangement and formation of parts, as will be hereinafter more specifically described, claimed and illustrated in the accompanying drawing, forming a part of this specification, and in which drawings:

45 Figure 1 is a side elevation of the improved eraser end showing the same attached to a fragment of the pencil, which can be of the type shown in my copending application.

50 Figure 2 is a longitudinal section through the same illustrating the novel means for supporting the eraser.

55 Figure 3 is a longitudinal section through the pencil end with the eraser and supporting spring removed therefrom.

Figure 4 is a detail transverse section taken on the line 4—4 of Figure 3.

Figure 5 is a side elevation of a modified form of the improved pencil end or eraser attachment showing the same applied to a 60 pencil of the type shown in my copending application.

Figure 6 is an enlarged longitudinal section through the modified pencil end or eraser attachment, showing the same applied to a pencil of the character set forth in the said copending application. 65

Figure 7 is a transverse section through the pencil eraser attachment taken on the line 7—7 of Figure 6. 70

Figure 8 is a longitudinal section similar to Figure 6, showing a further modified form of the improved eraser attachment.

Figure 9 is a detail transverse section taken on the line 9—9 of Figure 8, illustrating 75 the formation of the means for mounting the eraser follower within the attachment.

Figures 10 and 11 are detail elevations illustrating the modified forms of the attachments which are adapted to be particularly associated with ordinary types of pencils. 80

Referring to the drawings in detail, where-in similar reference characters designate corresponding parts throughout the several 85 views, the numeral 100 indicates the improved eraser attachment which can be associated with a pencil 110 which can be of the type shown in the co-pending application or other similar pencils having a detachable cap on the outer end thereof. 90

The improved attachment 100 includes a cylindrical body 101, the lower end of which can be flared as at 102, and internally threaded as at 103 for engaging the pencil 110. 95 The cylindrical body 101 adjacent to the flared portion 102 is provided with an inner partition wall 104, which can be provided with an axial opening 105. The inner surface of this cylindrical body 101 is provided with spiral guide ribs 106, the purpose of which will be hereinafter more fully described. An eraser body 107, of such a diameter as to readily fit within the cylindrical body 101, is fitted in the same, and as shown the outer surface of the eraser body 107 is provided with spiral grooves 108 for the reception of the spiral guide ribs 106. The ribs 106 can extend throughout the entire length of the body 101, if so desired, 110

- but the grooves 108 may extend only a part of the length of the eraser body 107. However, by providing the ribs 106 extending the entire length of the body 101 a relatively large supporting surface is formed for the eraser body 107. The body 101 also has fitted therein a coil spring 109, the inner end of which is provided with a bent terminal 111 for insertion into the opening 105. The outer end of this spring engages the eraser body and forms a support for the same. This spring is of just a sufficient tension to hold the eraser body against inward movement when the eraser is being used.
- When it is desired to move the eraser body outward after the same has become worn, it is merely necessary to grasp the end of the same with the fingers and give the same a slight twisting movement and pull the same outwardly. The spiral rigs, as stated, tend to hold the eraser body in position preventing the same from slipping out accidentally, and the coil spring functions as to lift and support the eraser.
- It is obvious that the outer surface of the body 101 can be milled or provided with threads in order that a grip may be obtained thereon to facilitate the adjusting of the eraser body 107. As shown, the pencil end is provided with a pocket clip 112.
- The letter A indicates a modified form of the eraser attachment in which a positive means is provided for feeding the eraser outwardly. The attachment A is particularly adapted to be associated with the pencil B of the type disclosed in my copending application or in other similar pencils having a detachable cap on the outer end thereof.
- The improved attachment A includes a cylindrical body 10, which is provided with interior threads 11, which may be cut into the same. These threads perform a dual function, first for connecting the attachment to the barrel 12 of the pencil B, which as shown is provided with exterior threads, and second for feeding the eraser follower in the body 10, as will be hereinafter more fully described.
- The extreme outer end of the body 10 is provided with an annular flange 15, for receiving a cap 16 thereon. This cap 16 may be made of any desired material, but preferably of hard metal, and is provided adjacent to its inner end with an annular groove 17. A connecting ring or collar 18 engages in the groove 17 and around the flange 15, and unites the cap 16 to the cylindrical body 10 for a purpose which will hereinafter more fully appear. The cap 16 is supported for rotatable movement by means of the connecting band, barrel or collar 18. If desired, the outer end of the cap 16 may be bevelled or cut inwardly, as at 19, so as to form a substantial continuation of the eraser body 10 when the outer end

thereof is flush with the outer end of the cap 16. The outer end of the cap 16 is preferably knurled, or otherwise serrated, as at 21, so that a firm grip may be had on the same.

If desirable, the outer surface of the body 10 may also be provided with longitudinally extending ribs 22, which will permit a ready grip to be had on the body. The cap 16 is provided with a relatively large bore 23 and the inner surface of the bore is provided with inwardly extending extensions 24, which are arranged in spiral or stepped formation. There may be as many of these extensions 24 as is practical or desirable, and it is preferred that at least three of the said extensions be used.

The eraser proper 20 can, of course, be constructed in any preferred manner of any desired material, and is provided with spiral grooves 25, which are adapted to receive the extensions 24. This prevents the free outward movement of the eraser and permits the same to be conveniently held within the cap 16. These grooves 25 may or may not be provided in the eraser body 20 as is desired, as the eraser body may be felt plain and the projections 24 will cut their ways into the surface of the eraser body as the same is forced into the cap. The inner surface of the eraser body is provided with a conical depression 27, the purpose of which will be hereinafter more fully described.

In order to feed the eraser body 20 outward of the cap C, a follower 30 is provided. This follower 30 is provided with a central body 31 and outwardly extending arms 32, which are provided with exterior threads for engaging in the threads 11 of the cap 10. Thus it can be seen that these threads perform the dual function of connecting the attachment to the pencil, and for holding the follower 30. Each of the arms 32 of the follower is provided with ways 33, through which freely extend guide rods 34. These rods 34 have their free ends secured in any preferred manner to the cap 16, to permit movement of the rods when the cap 16 is rotated. As shown by way of example, these rods are threaded into suitable sockets formed in the inner ends of the caps. The forward ends of the rods 34 are provided with heads 35 for limiting the inward movement of the follower 30 on the rods.

The rear face of the body 31 of the follower 30 is provided with a conical extension 36, which is adapted to fit in the conical depression 27 formed in the inner end of the eraser body 20. This serves as means for centering the eraser body 20 within the attachment.

In use of the improved attachment, the same is connected to the barrel 12 of the pencil B by means of the threads 11 on the body 10, and when it is desired to feed the

eraser body 20 outwardly of the attachment for any purpose, it is merely necessary to rotate the cap 16. The rotation of the cap 16 will turn the follower 30 through the medium of the rods 34, and as the follower is threadably connected to the body 10, the follower 30 will be moved outwardly, which will force the eraser body 20 outwardly.

10 When the eraser has become worn to such a point that it cannot be used any more, it is merely necessary to grasp the stub of the eraser with the fingers and pull the same outwardly with a slight twisting movement. 15 A new eraser body can be then inserted with in the cap.

It is of course apparent that the cap 16 can be connected to the body 10 in numerous other ways than that shown in Figures 5 20 and 6, and it is also apparent that the body 10 can be connected to the barrel 12 of the pencil in other ways than that shown. In Figure 8 is shown a modified means for connecting the cap to the shell or body, which 25 consists in providing a body 50, preferably formed of sheet metal, having threads 56 stamped into the same for engaging threads similar in form on the body 12 of the pencil B. In this form the outer end of the body 30 50 is turned over to provide an annular reinforcing and retaining ring 57, which is adapted to rotatably receive a cap 58, which is formed similar to the cap 16. This cap 58 receives an eraser body 20, the same as the 35 eraser body in the form above described, and the attachment is actuated in exactly the same manner in the modified forms as in the form shown in Figures 5 and 6.

It is also readily apparent that the 40 attachments may be provided with pocket engaging clips 59 as shown in Figures 1 to 6 of the drawings, or with loops or eyes 60 as shown in Figures 8 and 10 of the drawings. The loop 60 can be conveniently used 45 for permitting the pencil to be suspended by a chain when so desired. If so desired both clip and loop may be provided on the same attachment, or the attachment may be left entirely plain without any clip or loop.

50 In Figures 10 and 11 are shown means for respectively connecting the attachments C and D to ordinary pencils E and F. In Figure 10, the attachment C is provided with an inwardly extending sleeve 70, which is provided with an inwardly extending key hole slot 71, which adds resiliency to the sleeve and thus permits the same to be readily attached to pencil ends and to conform to the various diameters of different pencils. 55 The sleeve 70 is provided with a sliding ring 72, which is adapted to contract the inner end of the sleeve in order to bring the same into firm engagement with the pencil. This ring 72 may be provided with suitable pins 73 60 for engaging in recesses 74 formed in the

sleeve, so as to hold the ring 72 in its adjusted position.

In Figure 11, the attachment D is provided with a cylindrical sleeve 80, which is provided with inwardly extending spiral 70 ribs 81, which are adapted to frictionally engage the pencil end and hold the attachment in position thereon.

From the foregoing description, it can be seen that an improved eraser attachment 75 has been provided which can be conveniently connected to the ordinary types of pencils, or to special types of pencils which embody independent leads, which are adapted to be fed outwardly of the pencil at the will of 80 the operator, the improved attachment embodying novel means for permitting an eraser to be fed exteriorly of the same, so that all of the eraser can be conveniently used and thereby prevent waste and the like. 85

Changes in details may be made without departing from the spirit or scope of this invention; but,

I claim:

1. A pencil attachment comprising a 90 sleeve provided with threads, a follower threaded in said sleeve, means for detachably connecting the sleeve to a pencil, an eraser movably mounted within said sleeve and a rotatable cap carried by said sleeve, 95 and means operatively connecting said cap to said follower so that said follower will be rotated with said cap upon movement thereof and moved along said sleeve, whereby the eraser body will be fed outwardly of 100 the cap.

2. In an eraser attachment for pencils the combination with a pencil including a barrel having an exteriorly threaded end, a 105 sleeve interiorly threaded with respect to the barrel, a follower arranged in the sleeve provided with threads for engaging the threads in the sleeve, a rotatable cap carried by the outer end of the sleeve having a bore of relatively large diameter, an eraser body fitted within the bore, inwardly extending rods carried by the cap, the follower being slidably mounted upon said rod for movement longitudinally of the same, whereby upon rotation of the cap the follower will 110 be forced outwardly and the eraser body therewith.

3. An eraser attachment comprising a sleeve, a cap rotatably carried by the outer end of the sleeve having a bore of relatively large diameter, inwardly extending projections formed in the bore of the cap, an eraser body fitted within the bore of the cap provided with spiral ways arranged to receive said projection, a follower rotatably 120 and slidably mounted within the sleeve and threadably connected thereto, and means operatively connecting said follower with said cap. 125

4. An eraser attachment for pencils com- 130

- 4
- prising a sleeve including an interiorly threaded body for engaging the threaded end of the pencil, a cap having a relatively large bore rotatably carried by the sleeve, 5 inwardly extending rods carried by said cap, a follower including a central body and outwardly extending arms slidably mounted upon said rods and in screw threaded engagement with said sleeve, heads 10 formed on the inner ends of said rods for limiting the inward movement of the follower thereon, inwardly extending projections formed in the bore of the cap, and an eraser body fitted within the bore and receiving 15 said projections.
5. An eraser attachment for pencils comprising an internally threaded sleeve, a cap rotatably carried by the outer end of the sleeve having inwardly extending threaded 20 sockets formed in the inner face thereof, inwardly extending rods threaded into said sockets, a follower including a central body and radially extending arms, the outer faces of the arms being threaded for engaging in 25 the threaded portions of said sleeve, the arms having openings for slidably receiving the rods, heads formed on the inner end of said rods for limiting the inward movement of the follower on the rod, the inner end of the said follower body having a conical 30 extension formed thereon, an eraser body fitted within said bore in the cap having an axial inwardly extending conical depression arranged to receive the conical extension. 35
6. In an eraser attachment the combination of a body providing an opening therethrough and a projection extending into said opening, and an eraser provided with grooves therein adapted to receive the projection whereby the eraser may be supported in the opening of said member in a desired position against accidental longitudinal movement with respect thereto. 40
7. In an eraser attachment of the class 45 described the combination of a supporting cap provided with an opening therethrough and with projections extending into said opening, and an eraser having spiral grooves provided therein from its lower end and extending for a portion of the length thereof, said spiral grooves adapted to receive therein the projections of said cap with the eraser disposed in the opening of said cap in order to support the eraser in a desired 50 fixed relation with respect to the cap. 55

ALFRED A. E. HANSEN.
